PORTABLE REGISTER

John Q. Sherman and Albert W. Metzner, Dayton,
Ohio; said Metzner assignor to said Sherman

Application September 11, 1933, Serial No. 688,935

34 Claims. (Cl. 282—3)

This invention relates to autographic registers for manifolding purposes, and more particularly to a portable register of relative small size and light weight which may be conveniently carried from place to place in lieu of an ordinary clip board.

In checking shipments and taking inventory of bulky articles such as machinery, lumber, vehicles of grain, and for car checking and the like, it is customary for the accountant to carry from place to place record sheets slipped to a board supported upon his arm, upon which record entries are made.

In the present invention there are employed continuous series connected forms or record sheets with manifolding duplicates, the supply portions of which are enclosed in a comparatively thin housing or case of light weight material, preferably aluminum, from which successive portions of the record material are withdrawn as required, and the top of which forms a suitable writing surface. For preparation of shipping or identification tags to be applied to shipments, machinery, or articles in storage, and particularly for making work sheet records and tags when the register is used in vehicle drive-in places, for which it is especially desirable, means is provided for inserting in writing position beneath the manifolding material a separate sheet or tag upon which will be reproduced the manifolded inscription. The device is adaptable for feeding record forms or portions of different lengths and has provision for temporary storage of detached sheets or for a supply of blank tags.

The object of the invention is to simplify the construction as well as the means and mode of operation of portable manifolding registers, whereby they will not only be cheapened in construction, but will be more efficient in use, uniform in operation, of compact construction and light weight, and unlikely to get out of order.

Another object of this invention is to provide a small portable manifold register that will accommodate various lengths of forms. This has been accomplished by providing a group of interchangeable pin wheel feeding mechanisms of various sizes so that one revolution of a selected pin wheel feeding device will advance a suitable form the desired distance.

Another object of this invention is to provide a portable pin wheel feed manifold register that will accommodate various sizes of one revolution pin wheel devices for feeding different lengths of forms. This has been accomplished by provid-

ing a plurality of seats to accommodate the several sizes of pin wheel feeding devices in such a position that the pins of each feeding device when in position will extend the same distance beyond the writing material.

A further object of the invention is to provide improved means for mounting a plurality of sheets of transfer material between superposed strips, in such relation that the transfer sheets extend longitudinally of the strips, and enable the utilization of the full lengths of printed forms thereon, and to protect overlying strips from reverse impressions on the under sides due to overfolding of the end of the transfer sheets.

A further object of the invention is to provide a manifolding register which may be easily and conveniently carried from place to place and adapted to contain an ample supply of continuous series connected record material or forms.

A further object of the invention is to provide improved feeding means for progressively advancing the successive record portions from the interior of the housing or register box to writing position on top thereof.

A further object of the invention is to provide means for inserting at will beneath the manifolding material an additional sheet or tag to receive a duplicate inscription.

A further object of the invention is to provide means for carrying a quantity of detached sheets or a supply of blank tags.

With the above primary and other incidental objects in view, as will more fully appear in the specification, the invention consists of the features of construction, the parts and combinations thereof, and the mode of operation, or their equivalents, as hereinafter described and set forth in the claims.

Referring to the accompanying drawings, wherein is shown the preferred, but obviously not necessarily the only form of embodiment of the invention, Fig. 1 is a perspective view of the assembled autographic or manifolding register, forming the subject matter hereof. Fig. 2 is a longitudinal sectional view thereof. Fig. 3 is a perspective view with the top or cover portion of the register raised and disclosing the relation of the record sheets and carbon or transfer material. Figs. 4 and 5 are detail views, illustrating the mounting of the pin wheel feed device and its control means. Fig. 6 is an enlarged detail view of the tag receiving guide removed from the register. Fig. 7 is a perspective view of an identification tag and an overlying record

sheet, the latter being illustrated by dotted lines. Fig. 8 is a transverse sectional view. Fig. 9 discloses a modification of a stop for the pin wheel feeding mechanism. Fig. 10 is a perspective view of the register embodying a modification thereof. Fig. 11 is a perspective view, partly broken away, of the modified register in open condition with the transfer material mounting device disconnected therefrom. Fig. 12 is a detail view illustrating the relation of the transfer sheets and mounting means. Fig. 13 is a detail view illustrating the detachment of the transfer material. Fig. 14 is the detail view of a form or slip after detachment.

15 Like parts are indicated by similar characters of reference throughout the several views.

The present invention affords a simple, light weight, compact container for record material which may be conveniently carried from place to place and from which the record material is directed over the top thereof which affords a suitable writing cabinet on which the material may be inscribed. The record material comprises continuous superposed strips of material marginally punched at spaced intervals for engagement of pin type feeding devices, such strips consisting of successions of record sheets or of printed forms connected end to end and collectively interfolded in zigzag formation into a packet.

30 The record material is advanced by manually operable pin wheel feeding devices located in a substantially cylindrical compartment at the forward end of the record material compartment, which engage the marginally punched feeding holes of the record material and which are limited to one complete revolution at each operation. Guides are provided on the writing cabinet between the lines of feeding engagement of the pin wheels and record material within which 40 an additional record sheet or card may be slidably inserted to receive a manifold inscription.

Referring to the drawings, the present register housing comprises a flat rectangular box like compartment 1 open at its rearward end for 45 reception of a packet of folded manifolding material and having at its forward end a substantially cylindrical compartment 3 in which are revolvably mounted pin wheel feeding devices 4 intersecting the top of the compartment 3 and 50 having engagement in the marginal feeding holes 5 of the superposed strips of record material. The peripheries of the pin wheels 4 are equal to the length of the record sheets or forms to be fed at each operation. The cylindrical compartment 3 is of sufficient diameter to accommodate the largest pin wheel to be employed for the longest form or sheet accommodated by the compartment 1 and hence the diameter of the pin wheel compartment is commensurate to the 55 length of the compartment 1. To minimize weight and bulk, the box like compartment 1 is comparatively shallow and of less depth than the diameter of the pin wheels and the enclosing compartment 3, which depends below the bottom of the record material compartment 1.

The terminal heads of the pin wheel compartment 3 are provided with vertically elongated holes 6 across which are bridge bearing plates 7 in which are journaled the ends of the 70 pin wheel shaft 8. The bearing plates 7 are adjustably secured to the heads of the pin wheel compartment 3 by attachment screws 9. These screws are engageable alternately in different spaced holes 10 in the end walls or heads of the 75 pin wheel compartment. The bearing plates 7

are located interiorly of the terminal walls of the compartment 3 in which are located the vertically spaced holes 10. The bearing plates 7 are provided with screw threaded holes registerable with any pair of holes 10 of the compartment heads to receive the attachment screws 9. By shifting the bearing plates 7 upwardly or downwardly and engaging the attachment screws 9 through the corresponding holes 10, pin wheels of different diameter may be accommodated. 10 By such adjustment of the bearing plates 7, the peripheries of the pin wheels 4, whether of large or small diameter, may be made to intersect the top wall of the compartment to like extent for feeding engagement with the punched record 15 material.

Secured to the extremity of the pin wheel shaft 8, beyond the terminal head of the compartment 3, is a hand wheel 11 which is preferably, though not necessarily, of polygonal form and may be 20 provided with an eccentrically located crank handle 12 by which the pin wheels may be rotated. Located behind the hand wheel 11 and secured to the terminal head of the compartment 3 preferably by the attachment screws 9, is a depressible 25 spring arm 13 which extends into the path of a stud or pin 14 projecting from the rear side of the hand wheel 11. This stud or pin 14 is preferably a continuation of the crank handle 12. The spring arm 13 forms a stop for limiting the rotation of the hand wheel 11 and thereby the pin wheels 4 to one complete revolution. This stop arm is manually depressible out of the path of the stud or pin 14 to release the hand wheel 11 and pin wheels 4 for a further rotation. To prevent 30 reverse rotation of the feeding pin wheels 4, a gravity pawl 15 is provided, the nose of which is beveled on one side and substantially vertical on its opposite side, and is engageable in a notch or recess 17 in the pin wheel shaft 8. The detent 35 pawl 15 is extended downwardly at 18 to afford a counterbalancing or weight portion which tends to move the arresting nose 16 of the pawl into locking engagement within the notch or recess 17 when such notch or recess is brought into registry therewith. Upon rotation of the pin wheel shaft 8 in a forward or feeding direction, the engagement of the side of the recess or notch 17 with the beveled side of the detent nose 16 serves to cam the detent out of locking engagement and 40 permits rotary motion of the shaft. However, upon reverse motion, the opposite wall of the recess or notch 17, engaging against the vertical or flat face of the detent nose 16, prevents such reverse rotation of the shaft 8 which is thereby 45 resisted by the detent.

The superposed record strips drawn from the packet 2 within the compartment 1 are passed about a guide rod or roller 20 adjacent the rear and open end of the compartment 1, and are 50 passed through a transverse slot 21 in the top of the compartment and thence forwardly over the top wall of the compartment 1 which forms a writing tablet, into operative feeding engagement with the pin wheels 4 which protrude slightly 55 above the level of the writing cabinet through suitable located slots in the top wall of the compartment 3. Thus at each rotation of the pin wheels 4, the superposed strips of record material engaged therewith are correspondingly advanced 60 over the writing tablet or top of the compartment 1, the extent of such advance movement being determined by the peripheral extent of the pin wheels 4 which, as before mentioned, are limited to one complete rotation at each operation. The 65 70 75 75

record sheets or printed forms to be advanced are of a commensurate length so that at each rotation of the pin wheels, one complete record sheet or printed form is advanced beyond the device and another record sheet or printed form is withdrawn from the interior of the compartment 1 into writing position preparatory to making the next record.

Pivottally mounted, preferably though not necessarily, to the end walls of the pin wheel compartment 3, is a frame like swinging cover portion 23 which overlies the punched margins of the record material and defines the writing space. The rear or free end of such open frame like cover 23 is downturned at 24 to form a closure for the open end 25 of the record material compartment 1.

Located on the writing tablet or top wall of the compartment 1 inwardly beyond the line of feeding engagement of the pin wheels and record material are parallel guides 26 which underlie the strips of record material withdrawn from the compartment 1. At the forward end of the frame or housing overlying the compartment 3 is a slotted guiding portion 27 leading to the overhanging ledges or guides 26. A card or tag, as indicated at 28, may be slidingly inserted through the guide portion 27 beneath the guide flanges 26 and hence beneath the superposed strips of record material, into position to receive a manifold inscription thereon. Such card or tag 28 is not subject to advancement by the pin wheels 4 and is manually inserted and removed. The guides or overhanging ledges 26 are closed at their rearward ends as indicated at 29 to afford stops limiting the extent to which the card or tag may be inserted.

Located at one side of the compartment 1 is a compartment 30 for carbon or transfer material, having extending therethrough a shaft 31 upon which a roll 32 of carbon or transfer material is mounted. The strips of carbon material, of which there may be several interwound one within the other into the roll 32, are extended transversely of the writing tablet and interleaved between the superposed strips of record material, as is shown in Fig. 3, and between the lowermost strip of record material and the underlying card or tag 28. By this means such data or record as may be inscribed upon the uppermost or original record strip, is duplicated upon each of the underlying strips and also upon the inserted card or tag 28. As each record sheet or form is inscribed, the pin wheels 4 are manually actuated to advance such inscribed portion beyond the device and to draw a new uninscribed portion into writing position. At the same time the inscribed card or tag is slidely withdrawn and a new card or tag is inserted. To prevent the edges of the transversely disposed transfer sheets being mutilated or overturned by the friction of the traveling record strips, and to prevent the perforations of the latter being torn by contact with the edges of the transfer material, stationary shields or guide sheets 33, preferably of fabric, but which may be paper, extend into slightly overlapping relation with the transfer material as is shown in Fig. 3. These shields 33 are attached to transverse strips 33' attached to the writing tablet beyond the margins of the record strips. The underlying duplicate record strips pass between the mounting strips 33' and shields 33 whereby a pair of shields are provided beneath each strip 75 with their terminal margins overlapping and un-

derlapping the corresponding transverse strip of transfer material between such record strip and the transfer material. The lap is merely sufficient to protect the edge of the transfer material. To conveniently carry detached written forms or a supply of cards 28 there is provided beneath the compartment 1 a pocket 34 opening laterally and having an upturned lip 35 offset slightly beyond the side of the compartment 1. The upturned lip 35 serves to retain the cards 10 or tags within the pocket 34 from which they are removable by slightly bending the card or tag upwardly to clear the top of the lid 35. Thus a supply of cards or tags may be conveniently carried in readily accessible position. If cards 15 or tags 28 are not required the pocket 34 may be utilized for storage of used or inscribed record sheets or printed forms after they have been detached from the supply strips.

While the guide flanges 26 for the additional sheet or tag may be fixedly attached to the writing tablet or top of the compartment 1, these guides 26 are preferably mounted on a separate plate 36, the forward extremity of which forms one side of the guiding portion 27 by which the tag or sheet is directed into the guides 26. The guides and supporting plate 36 thus form a detachable unit to be applied and removed as necessity requires. Such unit is located upon the housing by means of short studs 37 projecting from the top of the housing 1 which engage in corresponding holes in the plate 36. When not required the unit is removed entirely, or it may be replaced by a different unit of greater or less length to accommodate other sizes of cards or tags.

In the modification disclosed in Fig. 9, the hand wheel 11 is held in a fixed position by the stud or pin 14 projecting into a recess or cutaway portion 52 in the split spring 54 carried by the screws 9. The spring 54 is provided with a slot 56 extending from the outer lower edge to the hole 52 and a second slot 58 extending from the hole 52 towards the adjacent screw 9. When the pin 14 engages the recessed portion 40, shown in Fig. 4, the lower and smaller portion 41 of the spring 54 yields to permit the pin 14 to enter the hole 52 whereby movement of the pin 14 and the wheel 11 is arrested. By pressing the button 42 from the full line position, disclosed in Fig. 9, to the dot-dash position, the wheel 11 is permitted to make another rotation, but cannot be retracted as the lower portion 41 is not affected by the movement of the upper portion 43. Thus by this structure the split spring 54, as already described, eliminates the use of the gravity pawl 15.

While transversely disposed transfer strips as heretofore illustrated and described, and which may be of any necessary or desired width are quite satisfactory, it is found desirable for certain conditions of use to employ transfer sheets disposed longitudinally of the record strips. Such embodiment is illustrated in Figs. 10, 11 and 12 wherein 44 is a mounting frame having a succession of parallel spaced slats 45 to each of which is to be connected a sheet of transfer material and between which slats with their connected transfer sheets the superposed record strips are threaded, as shown in Fig. 12. The mounting frame 44 is attached to the writing tablet by the screws or studs 46. The transfer sheets 47 are not attached directly to the slats of the mounting frame, but are carried by transfer strips 50 which are secured only at their ends. The transfer sheets 47 are preferably folded about the 75

transverse mounting strips 50, as clearly seen in Fig. 12. The extremities of the transverse mounting strips 50 are suitably attached as by rivets to fabric or paper shields 48 adapted to be folded about the respective slats of the mounting frame. Tensioning spring channels 49 are pressed over the fold of the shield or carrier 48 about the slat so as to grip the carrier or shield 48 and slat by inherent tension. The shields or carriers 48 are of sufficient length that the opposite ends of the carriers when folded about the slats of the mounting frame will extend into overlapping relation with the reversely folded portions of the transfer sheets 47. Thus the overlapping portions serve as shields to protect the overlying record strip from receiving a reverse impression from the overturned portion of the transfer sheet which is disposed face upward, and to hold the fold down in place and keep it from pulling out.

In the form of embodiment of the invention shown in Fig. 10 the lid 23 has a writing opening of reduced size, coincident with the farther advanced of two sets of forms on the writing tablet 25 and the lid thus covers the mounting frame 40 and the carriers of transfer sheets attached thereto, as is shown by dotted lines in Fig. 10. The transfer sheets 47 extend the full length of the forms to be inscribed, with their extremities 30 substantially coincident with the extremities of the writing tablet. The sheets are renewed from time to time by raising the record strips and substituting new transfer sheets for those engaged with the transverse mounting strips 50 of the carriers.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means 50 and construction herein disclosed comprise the preferred form of several modes of putting the invention into effect, and the invention is therefore claimed in any of its forms or modifications within the legitimate and valid scope of the appended claims.

Having thus described our invention, we claim:

1. In a pin feeding type manifolding register, a tablet, a pin wheel feeding device for supplying manifold material thereto, and a removable guide 60 mounted intermediate the tablet and the manifold material, and arranged to receive record material advanced therein to the writing position in a direction opposite to the direction of advancement of the manifolding material relative 65 to the tablet by the pin feeding device.

2. In a pin feeding type manifolding register, a tablet, a pin wheel feeding device for supplying manifold material thereto, and a removably mounted guide supported intermediate the tablet 70 and the manifolding material, said guide being arranged to present record material into the writing position intermediate the pins of said pin wheel feeding mechanism.

3. In a pin feeding type manifolding register, 75 a tablet, a pin wheel feeding device for supplying

manifold material thereto, an auxiliary device removably mounted intermediate the tablet and the manifold material, said auxiliary device being arranged to present in writing position record material advanced thereto in a direction opposite to the advancement of the manifolding material by the pin feeding device. 5

4. In a manifolding register for use with a packet of manifold material, a supply compartment therefor, a tablet, a pin wheel feeding device 10 for advancing manifold material from the supply compartment over the tablet, a guide supported intermediate the tablet and the overlying manifolding material, said guide extending longitudinally in the direction of the advancing 15 manifold material and being arranged to receive additional record material advanced to the writing position intermediate the pins of said pin wheel feeding mechanism.

5. In a pin wheel feeding type manifolding 20 register, a magazine, a writing tablet, a pin wheel feeding device, a pin wheel supporting device adjustably mounted and arranged to accommodate interchangeably various sizes of pin feeding devices, with the pins thereof projecting to like extent beyond the surface of the tablet to engage 25 the record material.

6. In a pin wheel feeding type manifolding register having a one revolution pin wheel actuating member, a locking mechanism for preventing the rotation of the pin wheel feed device, said mechanism including a resilient member having one end thereof fixed, said resilient member including a pair of bifurcated arms, one of which operates in response to the movement of 35 the pin wheel feeding mechanism for preventing return movement thereof when the pin wheel actuating member is advanced to home position, the other arm of which limits the advance movement of the pin wheel feeding device when in 40 home position and is manually releasable to permit the rotation of said pin wheel feeding mechanism through one revolution.

7. In a register device of the character described, the combination with a rotary paper feeding mechanism of a nonrepeat device therefor including a bifurcated spring arm, a stud carried by the rotary paper feeding mechanism into the path of which both furcations of the spring arms project, a cam surface on one portion of the arm engaged by the stud to press such arm portion out of its path when moving in one direction, said arm portion preventing return motion, the second portion of the arm forming a manually depressible stop for the stud normally 55 preventing continued motion.

8. In a manifolding register, a writing tablet, strip feeding means for advancing superposed record strips over the writing tablet, a stationary transfer material support associated with the writing tablet, including a stationary bar extending transversely of the path of travel of the strips and therebetween, a sheet of flexible material folded about the bar to afford overlying loose ends, and mounting means between the loose ends of the sheet of flexible material for attachment of a sheet of transfer material to extend therebeyond in the direction of travel of the strips. 60

9. In a portable manifolding register, a flat 70 relatively shallow magazine compartment for a supply of record material the top of which forms a writing tablet, and having an exit opening at one end thereof, a transversely disposed compartment having a depth greater than the depth 75

of the magazine compartment extending across the end of the latter opposite that containing the exit opening, feeding devices located in the transverse compartment and engageable with record material extending from the exit opening over the tablet to progressively advance such material and means for actuating the feeding devices.

10. In a portable register, a relatively flat shallow magazine for a supply of folded superposed strips of record material, from one end of which the record material is withdrawn over the top of the magazine which serves as a writing tablet, a transversely disposed compartment at one end 15 of the magazine of greater depth than the magazine for record material feeding means, revoluble pin wheel units mounted in said compartment and engageable with the record material withdrawn from the magazine, locating means for 20 additional record material on top of the magazine and overlaid by the record material supplied from the magazine, said locating means being accessible intermediate the pin wheel units for insertion of record material in a direction reversely 25 to the direction of feeding action of the pin wheel units and independently thereof, and stationary supporting means for transfer material interposed between superposed portions of record material from which sheets of transfer material extend 30 in the direction of travel movement of the strips of record material.

11. In a pin wheel feed type manifolding register, a writing tablet, an adjustable pin wheel feeding device support arranged to accommodate 35 any one of a plurality of pin wheel feeding devices of different sizes, said support being adjustably mounted with respect to the writing tablet, a pin wheel feeding device carried thereby, the pins of the pin wheel feeding device extending 40 beyond the surface of the tablet to engage the record material.

12. In a pin wheel feed type manifolding register, a writing tablet, a pin wheel feeding device support adjustable into a plurality of positions 45 to interchangeably accommodate various sizes of pin wheel feeding devices with the pins thereof projecting to like extent into engaging relation with record material positioned over said tablet.

13. In a pin feeding type manifolding register, a magazine for holding a supply of manifold material, a tablet, a pin wheel feeding device for supplying manifold material thereto from the magazine, and a removably mounted guide supported intermediate the tablet and the manifolding material, said guide being arranged to receive record material advanced to the writing position intermediate said pin wheel feeding mechanism.

14. In a pin wheel feeding type manifolding register having a pocket for receiving written material, a writing tablet, a pin wheel feeding device, a pin wheel compartment arranged to interchangeably accommodate various sizes of pin wheel feeding devices, and an adjustably mounted support associated with the compartment for supporting the pin wheel feeding device, the pins of which extend beyond the surface of the tablet to engage the record material.

15. In a writing machine, a support for transfer material, said support including a bar having a strip of transfer material folded thereon, a shield overlying the fold of the transfer material for protecting the record material, and a U-shaped clamp for clamping the shield in fixed position.

16. In a pin wheel feeding type manifold register having a one-revolution pin wheel actuating member, a locking mechanism including a bifurcated member having one arm operating in response to the movement of the pin wheel feeding mechanism for preventing return movement thereof when the pin wheel actuating member is advanced to home position, the other arm of which limits the advance movement of the pin wheel feeding device when in home position and 10 manually releasable to permit the rotation of said pin wheel feeding mechanism.

17. In a manifold register having a pin type feeding device, including control mechanism moving through a predetermined distance for 15 causing the pin feeding device to eject the written form and present a new form to the writing position, and locking means including a bifurcated member having one end fixed and the bifurcated end free, of which one arm prevents 20 advancement of said control mechanism excepting when released, and the other arm operates in response to the advance movement of said control mechanism to permit the same to enter 25 home position, said last mentioned arm preventing said control mechanism from being retracted from home position.

18. In a pin wheel feed type manifolding register, a writing tablet, a pin wheel feeding device and a support therefor adapted to interchangeably receive any one of a plurality of pin wheel feeding devices of different sizes to eject different form lengths per revolution, thereby accommodating various sizes of manifold record material, 30 the tablet and the support having a relative adjustment whereby the pins of the various pin feeding device may extend equidistant beyond the tablet to engage the record material.

19. A manifolding register for use with continuous length superposed strips of record material and form length transfer material, including a container for the supply of record material, the top of which forms a writing tablet over which the strips are extended from the container, and mounting means adapted to extend 45 intermediate the strips of record material for supporting the transfer material, said means including two flaps one of which overlies the other, and to one of which the sheet of transfer material is engageable, the other flap extending into 50 overlapping relation with a portion of the engaged transfer sheet to afford a protecting mask.

20. A manifolding register for use with continuous length superposed strips of record material and form length transfer material, including a container for the record material, the top of which forms a writing tablet over which the strips are adapted to extend from the container, and mounting means for the interleaved sheets of transfer material including a ladder like structure overlying the writing tablet comprising a series of transverse spaced bars interconnected with each other, between the succeeding bars of which the different strips extend, and flexible transfer material carriers connected with the 65 different bars and extending therefrom in superimposed relation intermediate the several record strips, and in like direction.

21. In a writing machine for use with continuous length superposed strips of record material and form length transfer material, a support for said transfer material, said support including parallel spaced bars adapted to extend across the record material, at least one of which has a strip 70 of transfer material connected thereto, a shield 75

connected to one of said bars for shielding a portion of the record material, and a means for detachably connecting said shield to said bar.

22. In a manifolding register for use with continuous length superposed strips of record material and form length transfer material, including a writing tablet, strip feeding means for advancing the superposed record strips over the writing tablet, a stationary transfer material support associated with the writing tablet including multiple spaced stationary bars extending transversely of the path of travel of the strips and therebetween, and a guard sheet of flexible material carried by one of the said support bars in superposed relation with a sheet of transfer material also attachable to one of said support bars and extending between the strips in the direction of travel thereof.

23. In a writing machine for use with record material having feed holes, a support for the writing material, a pin wheel feeding device the pins of which extend beyond the surface of the support for advancing the record material thereover, and a second support for adjustably supporting the pin wheel feeding device so as to present the pins in material feeding relation with the surface of the first support.

24. In a writing machine for use with record material provided with feed holes, a pair of supports one of which is adjustable, one of said supports supporting the record material, a pin wheel feeding device supported by said other support and arranged to have the pins project beyond said record material support to advance the record material thereover, the adjustment of the adjustable support enabling the feeding pins of feeding devices of different sizes to project in material feeding relation beyond the record material support.

40 25. In a pin feeding type manifolding register for use with marginally punched record material, a magazine for supplying writing material, a tablet, a pair of pin wheels for feeding the manifold material from the magazine to the tablet, said pin wheels engaging the leading ends of the record material in writing position, and a guide mounted upon the tablet, the width of the guide being less than the distance between pins engaging apertures in opposite margins of the record material whereby a strip narrower than the marginally punched record material may be fed to the guide intermediate the feeding pins.

55 26. In a manifolding register for use with continuous length record material, a magazine for supplying writing material, a tablet, a feeding mechanism including a pair of material engaging devices for engaging opposite margins of the record material to align the same, and a guide mounted upon the tablet, said guide being narrower than the distance between the engaged margins of the record material whereby a narrow strip may be supplied to the guide intermediate said engaged margins.

65 27. In a manifolding register for use with continuous length strips of record material, a magazine for the record material, a writing tablet, a feeding device including means for engaging opposite margins of the record material, said means engaging the leading ends of the material overlying the tablet, and a longitudinal guide, narrower than the distance between the engaged portions of the record material, said guide opening toward the leading ends of the record material whereby a strip narrower than the distance between the engaged portions of the

record material may be inserted from the leading ends of the record material into the guide.

28. In a portable pin wheel feeding type manifolding register having a plurality of compartments, one for receiving the written material, one for a supply of record material, and a third compartment, said register including a tablet, a pin wheel feeding device for supplying manifold material from the record material compartment to the tablet, the pin wheel feeding device being mounted in said third compartment and a removably mounted guide supported intermediate the tablet and the manifold material, said guide being arranged to receive record material advanced to the writing position intermediate said pins and said pin wheel feeding device.

29. In a portable pin wheel feed type manifolding register having a plurality of compartments one for receiving the written material, another for a supply of record material and a third compartment, one side of one of said compartments forming a writing tablet, said register including an adjustably mounted support mounted in said third compartment arranged to interchangeably accommodate various sizes of pin wheel feeding devices, the pins of the pin wheel feeding device extending beyond the surface of the tablet to engage the record material.

30. A manifolding register wherein continuous record material is progressively advanced from a supply compartment past a writing position including a feeding device engageable therewith, mounting means for differentially supporting one at a time different feeding devices of different size in feeding relation with the record material, means for operating the feeding device to advance the material a predetermined measured distance, at each operation, said feeding device being one of a plurality of interchangeable feeding devices of different sizes successively engageable with the mounting for advancing the material different predetermined distances to which said operating means is common.

31. A manifolding register wherein continuous record material is progressively advanced from a supply compartment past a writing position including a feeding device engageable therewith actuating means for operating the feeding device to advance the material a predetermined measured distance at each operation, said feeding device being one of a plurality of interchangeable feeding devices for advancing the material different predetermined distances, and mounting means for differentially supporting the interchangeable feeding devices one at a time in feeding relation with the record material.

32. In a manifolding register a holder having therein a magazine compartment for a supply of record material, feeding means for intermittently advancing the record material from the magazine compartment past a writing position, a writing tablet over which the material is advanced in one direction by the feeding means, said holder having an access opening through which additional record means may be adjusted in a reverse direction over the writing tablet into manifolding relation with the first mentioned record material.

33. A manifolding register wherein a continuous strip of record material is advanced from a supply compartment past a writing position including a pin wheel feeding device mounted therein, mounting means therefor adapted to differentially support one at a time several interchange-

able pin wheel feeding devices of different diameters for feeding different lengths of record material, and means for limiting the rotation of the pin wheel feeding device to a movement necessary to advance the record material a predetermined distance appropriate to the particular pin wheel device being used.

34. A manifolding register wherein a continuous strip of record material is advanced from a supply compartment past a writing position including a pin wheel feeding device mounted

therein which is one of several interchangeable pin wheel feeding devices of different diameters for feeding different lengths of record material, and mounting means therefor for differentially supporting one at a time the several interchangeable pin wheels of different diameters in substantially tangential relation with the path of advancement of the record material.
